UNITED STATES PATENT OFFICE.

MORRIS HALPERIN, OF BROOKLYN, NEW YORK.

LIFE-BELT.

1,259,978.

Specification of Letters Patent. Patented Mar. 19, 1918.

Application filed June 2, 1917. Serial No. 172,480.

To all whom it may concern:

Be it known that I, MORRIS HALPERIN, a citizen of the United States, and resident of the borough of Brooklyn, in the city and State of New York, have invented a new and useful Improvement in Life-Belts, of which the following is a specification.

This invention relates to a life belt or preserver, with the objects in view of providing a device of this character which is simple to construct; which may be very easily and quickly applied to the wearer; which, when applied, will not handicap to any sensible degree the freedom of movement of the wearer; which will permit the wearer to turn and rest either face downward or face up in the water; which is light; and which may be readily rolled up and stored in a relatively small space.

Another object is to provide certain improvements in the form, construction and arrangement of the several parts whereby the above mentioned and other objects may be effectively attained.

A practical embodiment of my invention is represented in the accompanying drawings, in which,

Figure 1 represents a face view of the device applied to the wearer.

Fig. 2 represents a plan view, partly broken away, and

Fig. 3 represents a section taken in the plane of the line III—III of Fig. 2, looking in the direction of the arrows.

The device comprises a main band 1 which may advantageously be composed of two layers of canvas or duck, as clearly shown in Fig. 3. This band portion 1 may be of such height as to extend approximately from the armpits to the abdomen of an average sized adult, and of such length as to encompass the front and sides of the body, without covering the back. I have found, in practice, that suitable dimensions are twenty by twenty-eight inches.

The canvas or duck members of the band 1 are firmly sewed together at their side edges, as indicated at 2, 3, and are also sewed together at a short distance from their side edges, as indicated at 4, 5, in order to provide pockets at the sides thereof adapted to receive flotation elements 6.

These last named elements preferably consist of airtight metallic tubes or cylinders, which are quite long with relation to their diameter and have both ends tapered, as

clearly shown in the drawings. I prefer to make these of some such material as copper in order to resist the oxidizing or corrosive action of salt water.

If desired, the elements 6 may be filled with gas, but I have found it satisfactory to use them in the form of air-containers without the injection of gas. A suitable

size for the elements 6, in order to provide ample flotation ability for the use of an adult, is eighteen inches in length and three inches in diameter. Such sized elements are

conveniently secured in a band of the dimensions stated above. As an additional safeguard, it will be observed that the flotation

elements are provided with partitions 6*, as shown in dotted lines in Fig. 2, which serve to divide them into three separate airtight chambers. Thus, in case a flotation

element should become punctured at any given point, it will not negative the buoyancy of the element as a whole.

After the flotation elements 6 have been placed in the pockets in the band 1, the top and bottom edges of the latter, 7, 8, may be firmly sewed together, which will close the ends of the said pockets.

In order to provide means for attaching the life belt to the wearer, a neck loop 9 is sewed and riveted to the upper part thereof, as indicated at 10, 11, and waist straps 12, 13, may be similarly fastened at the sides about midway the ends.

If desired, a suitable pocket may be formed in the front of the band 1 and near the top thereof, as indicated at 14, for the reception of a flask 15, designed to contain stimulant.

When the device is not in use, it may be rolled up in an obvious manner and stowed as is customary on shipboard. In order to apply the same, it is simply required to unroll, place the neck loop 9 over the head, pass the waist straps 12 and 13 around the back of the wearer, and tie the same in front, as shown in Fig. 1.

In this condition, the belt is firmly held in position; the flotation elements 6 are longitudinally disposed at the sides of the wearer so as to permit turning in the water from the face down position to a face up position; and the elongated shape and tapering ends of the said elements allow ample freedom of movement for the limbs.

While I have described this as a life belt, it will be understood that it is applicable

as a swimming jacket for use in bathing, and it is also to be understood that various changes may be resorted to in the form, construction and arrangement of the several parts without departing from the spirit and scope of the invention. Hence, I do not intend to be limited to the details herein shown and described except as they may be specifically included in the claims.

10 What I claim is:

1. An article of the character described, comprising a band of such width as to extend, when the article is in position for use, from the armpits substantially to the hips of the wearer, and of such length as to encompass the front and sides of the body of the wearer without covering the back, the said band being provided with a vertically disposed elongated pocket adapted to lie under each arm-pit of the wearer, extending from under the armpit approximately to the hips, and an elongated, cylindrical, taper-ended, metallic

- 20

flotation element secured in each of said pockets.

2. An article of the character described, comprising a band composed of two layers of cloth of such width as to extend, when the article is in position for use, from the armpits substantially to the hips of the wearer, and of such length as to encompass the front and sides of the body of the wearer without covering the back, the said layers of cloth being fastened together near their side edges to form a vertically disposed elongated pocket adapted to lie under each arm-pit of the wearer, extending from under the armpits approximately to the hips, and an elongated, cylindrical, taper-ended, metallic flotation element secured in each of said pockets.

In testimony, that I claim the foregoing as my invention, I have signed my name this 1st day of June, 1917.

MORRIS HALPERIN.
